UNITED STATES PATENT OFFICE.

WILLIAM J. REILLY, OF DENVER, COLORADO.

APPARATUS FOR REFINING OIL.

Application filed November 12, 1921. Serial No. 514,520.

To all whom it may concern:

Be it known that I, WILLIAM J. REILLY, a citizen of the United States, residing at the city and county of Denver and State of Colorado, have invented certain new and useful Improvements in Apparatus for Refining Oil; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of this invention is to provide a method and an apparatus for the fractionation and distillation of hydrocarbon or other oils by the application of external heat whereby distillation can be carried out under any desired degree of temperature and pressure.

20 The pressure and temperatures to be employed are dependent upon the chemical and physical characteristics of the liquids under treatment and the products of distillation desired. My apparatus has therefore been so designed that the requirement of any particular distillation can be met and carried out with a high degree of thermal efficiency and resultant economy as well as at a high rate of evaporation.

25 My device is also designed to give a high rate of heat absorption per unit of heating surface exposed to the products of combustion.

30 In order to more clearly describe my apparatus I shall refer to the accompanying drawings in which—

35 Fig. 1 is a transverse section of my improved still taken on line 1—1 (Fig. 2).

40 Fig. 2 is a longitudinal section taken on line 2—2 (Fig. 1).

45 Fig. 3 is a partial longitudinal section taken on line 3—3 (Fig. 1).

50 Figs. 4 and 5 are parted sections similar to that of Fig. 3 and showing slight modifications.

55 Fig. 6 is a modification similar to Fig. 3 in which the pump has been omitted.

50 The same reference characters represent the same parts throughout the various views.

55 My improved still is enclosed in a housing of fire brick in the same manner as a steam boiler: this housing consists of a front wall 1, side walls 2, back wall 3, arched roof 4, and a furnace 5 provided with the usual

grate 6 and doors 7. As the housing and the means employed for supporting the various members of my still are more or less conventional I shall not describe them in detail but restrict the description to the still itself.

60 I provide three horizontal cylindrical drums 8, 9 and 10, two of which (8 and 9) are located at the same height, one near the front wall and the other near the rear wall, drum 10 being located near the floor. The three drums are interconnected by means of banks of tubes in such a manner that the liquid under treatment can circulate from one drum to the other and thus attain a 70 rapid absorption and distribution of heat. Drums 10 and 8 are connected with a large number of tubes 11 which will be referred to as the main bank. These tubes are arranged, preferably, in three or more layers 75 and in staggered relation in order that all of the heated gases will be obliged to come in contact with some of the tubes. Directly back of the main bank of tubes 11 is a baffle wall 12 arranged with openings 13 distributed over its surface so as to cause a uniform distribution of heated gases through the bank of tubes.

75 Drums 8 and 9 are connected by a single bank of tubes 14 on the top of which is 80 placed a baffle wall 15.

85 Drums 9 and 10 are connected by a single bank of tubes 17 which are protected from contact with the heated gases by means of a wall 18.

90 A gas outlet flue 19 extends across the interior space of the still from side wall to side wall, and is provided along its length with a plurality of openings 20 which are graduated in area so that there will be a uniform 95 suction pressure across the still. The flue being, of course, connected with the smoke stack.

95 The lower drum 10 is provided with a longitudinal downwardly projecting baffle 100 21 whose function it is to cause the liquid to flow downwardly and across the drum near its bottom instead of directly across the top of the drum as would otherwise be the case. A pipe 22 extends the whole length of drum 10 directly below the openings into the front tubes of the main tube bank: this pipe has a relatively small opening located opposite each front tube end. The function of pipe 22 is to convey steam, gas or other fluid and 105 to mix the same with the fluid under treatment so as to increase the rate of circulation.

It will be noted that the arrangement described above results in a device having a voluntary and continuous circulation of liquid. The liquid in the main tube bank 11 being exposed to the hot gases near to the furnace become very hot and flow upwardly into drum 8. The liquid in the vertical tubes 17 being protected from the heat by means of a baffle wall 18 are the coolest and flow downwardly into drum 10, in the meantime the liquid levels in drums 8 and 9 are maintained substantially equal by means of tubes 14.

Located above the oil drums and at right angles thereto is a number of vaporizing drums 23, which are connected to drums 8 and 9 by pipes 24 and 25 respectively. Drums 23 are provided interiorly with a plurality of horizontally inclined vaporizing pans 26, the purpose of which will hereinafter appear.

Located within each of drums 23 and near the forward end thereof is a pump 27 driven by a motor 28 the purpose of which is to raise liquid from drum 8 to the upper end of the uppermost vaporizing pan 26. The liquid raised by pump 27 will then flow from one pan to the other until it is finally discharged on the bottom of drum 23 and passes downwardly into drum 9 through pipe 25 where it mixes with the other liquid and reenters the circulation. In flowing over the vaporizing pans the liquid vaporizes readily and the released vapors are carried off through pipe 29 and passed through a condenser where the pressure under which condensation takes place is controlled by controlling the rate of exit from the vapor drum into said condenser, the pressure in the condenser being, however, always less than that in the vapor drum.

In Fig. 4 I have shown a slight modification from that shown in Fig. 3. Instead of having a pump inside driven by a motor on the outside of the drum, I have shown the pump and engine as one combined structure 29. The engine being operated by steam supplied through pipe 30 and exhausted through pipe 31.

In Fig. 5 I have shown another modification in which the pump 32 and engine 33 are both placed outside of the vapor drum 23. The pipe 24 being, of course, modified so as to conform to the changed location of the pump.

The drums are supported in a suitable way from I-beams 35, drums 8 and 9 being suspended from beams 34 by means of straps 36 and drums 23 being similarly suspended by straps 37.

Drums 23 are each provided with a safety valve 38 which is connected to a pipe 39 leading out to a suitable place of exhaust. Each drum is also provided with a pressure gauge 40 and thermometer 41 by means of which

the operator is enabled to tell the conditions under which the still is working, and by which he is governed in controlling the distillation.

Drum 8 is provided with a gauge 42 for indicating the level of the oil.

Drum 9 has connected thereto a supply pipe 43 through which liquid to be treated enters and drum 10 is provided with a pipe 44 connected to the bottom thereof and through which the still is emptied.

From the above it is seen that I have invented a still in which a large amount of oil can be subjected to treatment; in which a rapid, voluntary circulation of oil takes place, resulting in a rapid transfer of heat and the prevention of unequal and excessive heating of the metal parts of the still.

The operation of my device is as follows:

The oil to be treated is supplied to drums 8, 9 and 10 in sufficient quantity to fill drums 8 and 9 to a height somewhat above the level of pipes 14, the gases from furnace 5 then pass through the main tube bank 11; through the openings 13 in baffle wall 12 and into the transverse chamber.

Circulation of the liquid under treatment then commences, the heated oil passing upwardly through tubes 11 into drum 8, thence through tubes 14 into drum 9 and downwardly through tubes 17 into drum 10 from whence it again enters tubes 11 and begin a new cycle.

When the pressure and temperature has reached the proper values, pump 27 is started and liquid is lifted from drum 8 to the upper end of the uppermost vaporizing pan 26 from whence it flows from one pan to another until it finally reaches the bottom of drum 23 and enters drum 9 through pipe 25 where it mixes with the remainder of the oil under treatment.

The action of the pump in removing a portion of the oil from drum 8 has a tendency to lighten the weight in this drum and thus increase the rapidity of circulation, at the same time the oil from vapor drums 23 adds to the weight in drum 9 which also has a tendency to increase the rapidity of the circulation.

The vapors which are released in the vaporizing chambers of drums 23 are conducted away through pipes 29 to condenser 47' from which it issues in liquid form through valve 46. The exit pipe of the condenser has a pipe 49 connected thereto for the purpose of conducting away the uncondensed vapors; this pipe is controlled by valve 48.

The pressure under which condensation takes place is controlled by the manipulation of valve 45, which controls the exit of vapors from the vaporizing drums, and valve 46 which controls the rate of discharge of the condensed liquid from the condenser.

In Figs. 3, 4 and 5, I have shown an arrangement for raising the liquid from drum 8 to the end of the uppermost pan 26, which comprises a pump. I have, however, 5 found that a pump is not essential at all times and in Fig. 6 I have shown a modification in which the pump has been omitted and pipe 24 extended to the top of the uppermost pan 26. When my apparatus is in 10 operation the oil in pipes 11 becomes intensely heated and partially vaporized. This vapor mixes with the oil and reduces its specific gravity to such an extent that the column of oil in pipes 17 and tank 9, which 15 is free from vapor, will be able to raise the frothy oil in pipes 11 and cylinder 8 to the top of the uppermost pan 26. In order to dispense with the pump and raise the oil, by means of which depends upon the difference 20 in the specific gravities in pipes 17 and 11, it is necessary to so proportion the combined areas of pipes 14 that the liquid as it enters drum 8 will not be able to return to drum 9 as fast as it enters drum 8. The 25 excess over the capacity of pipes 14 will then be forced to pass upward through pipe 24 and take part in the major circulation.

I want to emphasize at this point the fact that I attain a double circulation in my still. 30 A portion of oil will circulate in pipes 11 to drum 8, through pipes 14 to drum 9, thence through pipes 17 to drum 10, from which it enters pipes 11 at the beginning of a new cycle; this I call the minor circulatory cycle. 35 A portion of the oil which enters drum 8 passes up through pipe 24 and is deposited on the upper end of the uppermost one of pans 26, and finally enters drum 9 through pipe 25; this I term the major cycle.

40 My still as described above comprises a figure eight arrangement, in which there are two paths in parallel for the oil that enters drum 8. By this means a portion always passes through the major circulation cycle 45 where it is subjected to intense evaporation, and re-enters the circulation at drum 9 where it mixes with the balance of the oil.

Tubes 11 are arranged at an angle of forty-five (45) degrees for the purpose of obtaining 50 the most efficient operation. With the tubes arranged at this angle, the gases will impinge on them at substantially right angles, and thus brush off any cooled gases that would otherwise adhere thereto. The 55 oil will also flow at a more satisfactory speed through tubes inclined at 45 degrees, than it will in horizontal or vertical ones.

It is also my object to space the fire on the grates at such a distance from the pipes 11 that little or no radiant heat will strike them, as by doing so I will get a more uniform 60 distribution of heat on the pipes 11.

Having described my invention, what I claim is:

1. A still for the fractionation of organic 65 oils comprising a furnace, an oil containing device consisting of three oil drums connected by tube banks to form a triangle with its apex at the bottom, said furnace having a passageway leading therefrom, one tube 70 bank being located towards the front of the furnace and in the passageway from the furnace, another of the said tube banks being located to the rear of the furnace and protected by means of a baffle wall located between the tubes and the furnace, a vaporizing drum located above the upper two oil drums aforesaid and having each end connected to separate ones of the oil drums, horizontally inclined vaporizing surfaces in 80 said vaporizing drum, means for elevating heated oil from one of the oil drums to the upper part of the uppermost vaporizing surface, means to return the unvaporized part of said oil to the other oil drum and means 85 for conducting the liberated vapors from said vaporizing drum.

2. A still for the fractionation of organic oils comprising in combination a furnace, cylindrical oil drums, a tube oil heater composed of three sets of tube banks arranged in the form of a triangle and having their ends connected to said cylindrical oil drums, the base of said triangle being on top and substantially horizontal, a vapor drum above 95 said base said drum having means for connecting one end to one of said oil drums, the other end of said vapor drum being provided with a pump for elevating oil from one of said oil drums to the vapor drum, a plurality 100 of horizontally inclined vaporizing surfaces extending lengthwise of said vapor drum, means connected to said pump for conducting heated oil to the upper part of the uppermost vaporizing surface, means for conducting 105 the vapors away from said drum to a condenser and means for controlling the pressure at which condensation takes place.

3. In a still for fractionation of hydrocarbon and other organic oils, means for heating the oil to any desired temperature, a vaporizing drum located above the heating means and having one end connected thereto by means of a pipe, said drum being provided in its interior with a plurality of oppositely and horizontally inclined vaporizing pans so arranged with respect to each other that the lower portion of each is directly above the higher portion of the pan 115 directly beneath, whereby any liquid deposited on the upper portion of the uppermost pan will flow from one pan to the other until it is finally deposited on the bottom of the vapor drum, and means for transferring oil 120 from the heating means to the upper portion of the uppermost pan.

In testimony whereof I affix my signature.
WILLIAM J. REILLY.
